UNITED STATES PATENT OFFICE.

STEPHEN B. FETHEROLF, OF CINCINNATI, OHIO.

LOCKING TOWEL-RACK.

1,289,428.

Specification of Letters Patent. Patented Dec. 31, 1918.

Application filed September 12, 1918. Serial No. 253,756.

To all whom it may concern:

Be it known that I, STEPHEN B. FETHEROLF, a citizen of the United States, and a resident of Cincinnati, in the county of 5 Hamilton and State of Ohio, have invented certain new and useful Improvements in Locking Towel-Racks, of which the following is a full, clear, and exact description, reference being had to the accompanying 10 drawings, forming part of this specification.

The present invention is fully set forth and described in that certain application for Letters Patent on locking towel racks filed by me April 5th, 1913, Serial No. 759,203, 5 certain claims of which are involved in the interference with the patent to Jacques Rousse, No. 1,157,046, dated October 19, 1915, and with the pending applications of Harry Solomon and Edwin T. Brigham; 10 and the present application is filed for the purpose of withdrawing from said original application the subject matter adjudged not to interfere.

My invention relates to towel racks, and 5 has for its object the prevention of removal and misuse of towels by the customer of a towel-supply establishment, and also prevent misappropriation of the towels by the delivery man, should he be dishonest, or loss 10 of towels by him, should he be careless.

My invention consists in the parts, and in the details of construction and arrangement 5 of parts, set forth and claimed herein.

In the drawings, Figure 1 is a sectional view of a towel cabinet with towels therein held on my improved towel rack, with dotted lines indicating the position of the towel and of the parts, when the towel is being used. This view illustrates the application 10 of my invention to the holding of hand towels.

Fig. 2 illustrates the use of my invention with a roller towel.

Fig. 3 is supplementary to Fig. 2 in illustrating at *a*, *b* and *c* respectively, different positions of the towel and the chain, as the 100 towel is being used.

Fig. 4 is a perspective view of a bundle of towels ready for delivery, with my improved device holding them.

Fig. 5 illustrates the part of the rack holding the soiled towels, ready for collecting them for return to the towel-supply house.

Fig. 6 illustrates, in section similar to Figs. 1 and 2, the use of a modification of

my invention, simpler in construction but less convenient in use.

Fig. 7 is a perspective view of a bundle of towels ready for delivery, with this modified device holding them. 60

Fig. 8 is a longitudinal sectional view of the tube and rod of this modified construction, with the chain thereon, but indicated as with a part broken away, for lack of 65 space.

Fig. 9 is a longitudinal sectional view of the device shown in Figs. 1 to 5, only part of the chain being shown.

Fig. 10 is a detail view of the inner member. 70

Fig. 11 is a similar view of the outer member.

Fig. 12 is a cross section on the line *x*, *x*, of Fig. 10. 75

Fig. 13 is a similar cross section on the line *y*, *y*, of Fig. 11.

Fig. 14 is a cross section through the lock-case, on the line *z*, *z*, of Fig. 9.

In the preferred form, the use of which 80 is illustrated in Figs. 1 to 5, and the parts of which are illustrated in detail in Figs. 9 to 14 inclusive, a lock-case 1 has a shank 2 that may extend through the bottom of the cabinet and receives a padlock, as seen in 85 Fig. 1.

Extending in opposite direction from the shank 2 is a barrel 3 having a pin 4, extending radially inwardly a short distance from the junction of the barrel with the lock-case. Inside the lock-case 1 are sliding keepers 5 and 6, pressed up by individually yieldable springs 7 and 8. The outer lock member 9 slides into the barrel 3 and has a longitudinal slot 10 extending from 90 the adjacent end of the member up to and merging into a slot 11 extending about one-fourth of the circumference of the tumbler. Diametrically opposite this slot 10 are two notches 12 and 13, cut about half-way 100 through the tumbler, each approached by a short incline 14 and 15 respectively, at their lower sides, while the lower notch 13 has a similar incline 16 at its upper side, and the end of the member on this side has a similar incline 17.

The outer locking member 9 is tubular, and the inner member 18, which need not be tubular, slides into the outer member. This inner member 18 has a longitudinal slot 19 110 merging into a circumferential slot 20, and on the opposite side has notches 21 and 22,

all of which register with and conform to the corresponding slots and notches in the outer member. The notches in this inner member, however, need have no inclines, 5 and the end of the member need not be inclined, as in the outer member.

The outer member 9 has a head or knob 23 obstructing the end of the barrel 3 when the keepers 5 and 6 are in the notches in the 10 outer lock member, as seen in Fig. 9. The inner member 18 has a chain 24 swiveled to its outer end, in a reduced region 25, so that the outer member 9 is permitted to slide out off the inner member onto this chain. The 15 chain has a ring 26 at its free end, preventing the outer member from leaving it. This chain may be of any length for convenience.

The towels have gromets 27, preferably 20 of metal, and these gromets slide onto the barrel of the lock when the outer member 9, with its obstructing head or knob 23 is removed from the lock. Then, when the outer member, with its head, and the inner member 18, with its chain with the ring on its 25 end, are placed in the lock, the towels may be slid out onto the chain, but only after the outer member has thus been slid out; and the outer member must go in advance of the towels toward the end of the chain, while 30 to replace the outer member in the lock, the towels must slide back onto the barrel of the lock in advance of the outer member.

With this arrangement, the outer member 35 being released and allowed to drop to the end of the chain, as in Fig. 1, the towels are free to be used, as indicated, but confined to the chain. The chain being flexible, offers very little interference with the use of the 40 towel and causes very little inconvenience to the user. If the device be locked into the cabinet, as indicated, the towels not only cannot be removed singly, but they cannot be removed without taking the cabinet with it. The first circumstance prevents misuse of 45 towels, such as using them for window cleaning or other work which spoils them; while the latter restriction discourages the transfer of the towels from place to place about the premises of the user, or away from his 50 premises, which may result in loss of the towels, with difficulty of fixing the responsibility.

The apparatus just described depends for 55 its security on the difficulty of removal of either member without leaving the other one in the lock, *i. e.*, the removal of both lock members so as to have both out during the same period of time. The delivery man can remove the inner member with its chain, but 60 only after he has placed all the towels on the barrel of the lock, where they belong for return to the supply house, and after the outer member has been secured in the barrel, with its knob or head preventing the escape of the towels from the barrel. The very act

of releasing the inner member requires the insertion and securing of the outer member in place. On the other hand, the customer or user, if he attempt to remove the towels, can only do likewise, and his attempt will be 7 frustrated.

The person responsible for all of the towels at the supply house has a key, in all respects like the inner lock member, except that no chain and ring are attached to it. 7 This key is inserted, releasing the outer member and allowing it to be slid out over the key, after which the used towels are removed over the end of the key, and clean towels replaced on the barrel of the lock, 8 sliding over the end of this key. Then the outer lock member is inserted again, releasing the key, but securing itself in place, with its knob preventing the removal of the clean towels. The delivery man may now take 9 the towels to the user, there insert the inner member with its chain and ring, which were left there when the last lot of used towels were removed, release the outer member and allow it to slide onto the chain, upon which the towels are ready for use, but cannot be removed, either by the delivery man or the customer. It is to be noted that the manager or person responsible for the towels at the supply house, could not remove his key after removing the inner lock member. It was only due to the fact that this key had no chain and ring that he was able to remove and replace the towels.

This removal of one lock member through the instrumentality of the other, thus making each member the key for the other, is effected by the partial rotation of either of them in the direction permitted by the circumferential slot riding over the radial pin 4. Such movement presses the keepers 5 and 6 down, against the pressure of their springs, disengaging these keepers from the notches in the other lock member, which was not thus turned, but which is turned so that its longitudinal slot rides over the pin 4, permitting it to leave the barrel. The one which was turned to disengage the keepers, however, has the pin engaging the sides of the circumferential slot, and cannot be moved lengthwise of the barrel. If this lock member be rotated back so that the pin is in line with its longitudinal slot, the keepers will immediately enter its notches, and they will prevent its longitudinal movement.

The actions of the outer and inner members in this operation are the same, except that the inner member, on partial rotation, as described, presses the keepers back only as far as the inner walls of this outer member on the inclines 14 and 15. Likewise, when the outer member is reinserted, the incline 16 at the upper side of the lower notch 13 and incline 17 at the end of the outer member come into action, pushing the

keepers back from the surface of the inner member to which they have been forced by the partial rotation of this member, and allowing the keepers to ride up onto the outer surface of the outer member, and then down the other inclines into the notches of this member against the surface of the inner member again, which, now rotated back, permits these keepers to enter its notches and the notches of the outer member as well.

A plurality of these keepers is provided to augment the difficulty of picking the lock when either one of the tumblers has been removed. The construction involving the action of the inclines to complete the removal of the keepers from the notches of the outer member also adds to the difficulty of picking the lock while the inner lock member is out, by access through the hollow interior of the outer lock member. By adding to the number of keepers, each with an individual spring and a notch to enter in each member, the difficulty of picking increases at a high ratio. The rightful operation of the lock will be equally convenient with any number of keepers, since it is necessary only to rotate the member which it is not desired to remove over till the end of the circumferential slot strikes the radial pin, and then rotate the other lock member desired to be removed in the other direction, at the same time pulling outward upon it. As soon as its longitudinal slot comes opposite the radial pin it will slide out. The operation of the lock is far more convenient and rapid than where a lock requiring a key is used, and the necessity of carrying a key is avoided. The lock-case and barrel, with the outer lock member in place, are the only parts that must go with the bundle of towels during transportation, the chain and inner member remaining at the place where the towels are used, and simply having various lock-cases, barrels and outer lock members interchanged with it, as successive bundles of towels are brought and taken away. Thus the delivery man is relieved of considerable labor of handling and transporting which is involved with apparatus requiring the entire apparatus to be taken along with the towels each time.

The simpler device which I illustrate herein has the advantage in common with the preferred construction above described, in that a chain is used, allowing free use of the towels while confined thereto. However this construction requires the use of a padlock with key, or other lock distinct from the towel holding elements, and it requires that the entire device be transported along with the bundle of towels each time. When thus transported, the chain may be wound around the bundle, as indicated in Fig. 7. The second lock, holding the apparatus in the cabinet performs the same function as

the similarly used one in the previous example; but it is necessary for the delivery man to have the key for this lock, as in the other example also. It will be understood that this lock, in either example, is not necessary to the prevention of loss of towels separately, but only to prevent bodily removal of the entire supply, as before described.

This simpler device comprises a tube 30 with a flange 31 at its lower end, and a rod 75 32 passing through the tube. The upper end of the rod has the chain 33 swiveled to it, with a ring 34 on the end of the chain. The gromets of the towels are slipped onto the tube, down against the flange, and then the 80 rod is inserted through the tube, after which the towels can be slid out onto the chain for use, but cannot leave the chain at the free end on account of the obstruction afforded directly by the ring. The rod has an upper 85 opening 35, adapted to come just below the flanged lower end of the tube when the rod and tube telescope. This opening receives a suitable lock to prevent withdrawal of the rod from the tube, and the key or other 90 means of opening this lock is kept by the manager or other person responsible for all of the towels, thus preventing the delivery men from separating the towels from the bundle. The lower opening 36 in the rod, 95 close to the lower end of the rod, receives the lock for locking the entire device with the towels in the cabinet, as before described. The delivery man carries the means for 100 opening this lock, so he can remove the entire device, with the towels, from the cabinet, to insert another complete device, with clean towels.

My device, of either construction, with the chain, is especially adapted for hand towels. By looping or hooking the chain to the cabinet it may be caused to hold a single towel if repeated use is desired. In any case, when the soiled towel is released, it slides toward the end of the chain, preferably into a suitable receptacle, as illustrated. Either construction is also highly adapted for use with roller towels, as illustrated in Figs. 2 and 3. The towel may be placed on the roller with the gromet close up to the roller on the front shelf. Then as the towel is used, the gromet slides down the chain until it reaches the bottom of the loop which the towel makes. The gromet then slides up the chain until it is ready to pass over the roller again, 115 where further movement of the towel in that direction is arrested. To use the towel again it is only required that it be pulled back until the gromet reaches the initial position. When a clean towel is desired, the soiled 120 towel is released from the roller as usual and allowed to slide down the chain bodily, after which a clean towel is brought down and placed on the roller. The flexibility of the chain permits the removal, use 125 130 135

and replacing of towels with scarcely any interference from the apparatus, while these roller towels are protected against misuse or removal just as the hand towels are.

5 It will be understood that my invention is adaptable for use in any connection where a quantity of towels are to be supplied and protected as described, and its use is not limited to association with cabinets or other 10 details as illustrated for example. Also the invention itself is capable of considerable modification other than is illustrated, without departure from the scope and spirit of my invention.

15 Therefore I do not wish to be understood as limiting myself to the specific details of the examples illustrated and described herein, but what I claim as new and desire to secure by Letters Patent, is:

20 1. The combination of a tube arranged to hold towels or the like by being threaded therethrough, a member supporting said tube, a flexible linear member adapted to be passed through the hollow interior of the 25 tube, a lock for detachably connecting said flexible linear member to the said supporting member after the said flexible linear member has been threaded through the said tube, and means at the opposite end of the 30 said flexible linear member for preventing the said towels or the like from being taken off, substantially as described.

2. A towel rack comprising a flexible member to receive the towels for use, a rod 35 secured to the flexible member, a tube receiving the rod and adapted to receive the towels from the flexible member for storage or transportation, and means for locking said rod in said tube.

40 3. A towel rack comprising a flexible member to receive the towels for use, an obstruction preventing the towels from being removed over one end of the flexible member, a rod secured to the flexible member, onto 45 which the towels may slide from the other end of the flexible member, a tube receiving the rod, and adapted to receive the towels from said rod and flexible member for storage or transportation, means for locking said 50 rod and said tube together, and means for locking said rod and tube, thus locked together, to the place of storage of the towels.

4. In a towel rack, as parts thereof, a lock-case, a barrel thereon, an outer lock member 55 inserted in the barrel, an inner lock member inserted in the outer member, and engaging means inside the lock-case to hold either of said lock members, but releasable by one of the members to permit the removal of the 60 other member, whereby the member releasing the engaging means is then held by said engaging means.

5. In a towel rack, as parts thereof, a lock-case, a barrel thereon, an outer lock member 65 inserted in the barrel, an inner lock member

inserted in the outer member, flexible towel-engaging means secured to the inner member, the towels being slideable on the flexible means and from there onto the barrel when the inner member is inserted, and the outer member being slideable out onto the flexible means, means on the outer member to confine the towels to the barrel when the outer member is inserted in the barrel, engaging means in the lock-case to hold either one or both of said members inserted in the barrel, but operated by either member to release the other member, whereby the said member releasing the engaging means is held by said engaging means.

6. In a towel rack, as parts thereof, a plurality of telescoping lock members, each acting as the key to release another, and each being held after it has released the other.

7. In a towel rack, as parts thereof, a plurality of telescoping lock members having recesses communicating, and a keeper entering the recesses, but expelled from said recesses by rotation of either member, and means preventing the withdrawal of the member that is rotated to expel the keeper, for the purposes set forth.

8. In a towel rack, as parts thereof, a plurality of telescoping lock members having transverse recesses communicating, a keeper entering the recesses, but expelled from said recesses by rotation of either member, said members also having longitudinal slots merging into circumferential slots, the respective slots of the members communicating, and a projection entering said slots, and occupying the circumferential slot in a member when it is rotated to expel the keeper, for the purpose set forth.

9. In a towel rack, as parts thereof, a plurality of telescoping lock members, each having a plurality of transverse recesses, the respective recesses of the members communicating, a plurality of keepers, each entering respective communicating recesses in the members, said members also having longitudinal slots merging into circumferential slots, the respective slots of the members communicating, and a projection entering said slots, and occupying the circumferential slot in a member when it is rotated to expel the keepers from the transverse slots.

10. In a towel rack, as parts thereof, a plurality of telescoping lock members, each having a plurality of transverse recesses, the respective recesses of the members communicating, a plurality of keepers, each entering the respective communicating recesses in the members, but expelled from its recesses on rotation of one of the members and means preventing the withdrawal of the member that is rotated to expel the keepers, for the purposes set forth.

11. In a towel rack, as parts thereof, a plurality of telescoping lock members, each

having a plurality of transverse recesses, the respective recesses of the members communicating, a plurality of keepers, each entering respective communicating recesses in the members, but expelled from said recesses by rotation of either member, individual yieldable means for each keeper, pressing it into its recesses in the members, said members also having longitudinal slots merging into circumferential slots, the respective slots of the members communicating, and a projection entering said slots, occupying the longitudinal slot of a member when its transverse recesses are adapted to receive keepers, but occupying the circumferential slot of a member when the member is rotated to expel the keepers from the recesses.

12. In a towel rack, as parts thereof, a plurality of telescoping lock members, each having a transverse recess, the recesses of the members communicating, a keeper entering the recesses in the members, but expelled from said recesses by rotation of either member, said keeper being expelled from the recess of the outer member by the rotation of the inner member only as far as the outer surface of the inner member, and the outer member having inclined surfaces for said keeper to pass over and be expelled to the outer surface of the outer member, for the purpose set forth, and means preventing the withdrawal of a member when it is rotated to expel the keeper.

13. In a towel rack, as parts thereof, a lock-case, a barrel on said lock-case, an outer lock member inserted into the barrel, an inner lock member inserted into the outer member, said members projecting into the lock-case, a pin inside the barrel, said members having longitudinal slots merging into circumferential slots, and the respective slots of the members communicating and receiving said pin, being allowed to be withdrawn from said barrel when the pin occupies the longitudinal slot, but being held in the barrel when the pin occupies the circumferential slot, said members also having communicating transverse notches in their parts projecting into the lock-case, a keeper entering the transverse notches when the pin in the barrel occupies the longitudinal slot, and being expelled from the notches when either member is rotated and admits the pin in the barrel to its circumferential slot, whereby either member may be released by the other, but whereby the one releasing is then held in the barrel, said

barrel being adapted to receive towels, obstructing means on the outer member to hold 60 towels on the barrel when the outer member is inserted in the barrel and held by the keeper, and a flexible member secured to the inner member and permitting the outer member to slide onto it, and thereafter the 65 towels to slide onto it, for use, and obstructing means on said flexible member to prevent the removal of said outer member and said towels from the flexible member.

14. In a towel supply device, a holder for 70 towels adapted for the use of said towels individually, means for locking said towels on the holder without interfering with the use thereof, a rack, and means for mounting the holder on the rack and removing it 75 therefrom without unlocking the holder to release the towels, said holder when mounted on the rack being adapted to allow the towels to rest on said rack.

15. In a towel supply device, a holder for 80 towels adapted for use of said towels individually, means for locking said towels on the holder without interfering with the use thereof, a rack, and means for locking the holder on the rack and unlocking it there- 85 from without unlocking the holder to release the towels.

16. In a towel supply device, a holder upon which to string towels, a flexible member inserted in said holder and locked there- 90 to, means on the flexible member for preventing the removal of towels therefrom, a rack, and means for mounting the holder on the rack without unlocking the flexible member. 95

17. In a towel supply device, a holder for towels comprising in part a rod, a rack, means for mounting the rod on the rack so that the towels thereon will lie on the rack, and means for locking the towels on the rod, 100 said means for mounting the rod on the rack being independent of the towel locking means whereby the rod and towels may be removed without unlocking the towels from the rod. 105

18. In a towel supply device, a holder for towels comprising a rod and a chain, a rack, means for mounting the rod on the rack so as to stand vertically with the chain depending therefrom, means for locking the towels 110 on the rod and chain, said means being independent of the means for mounting the rod on the rack whereby the rod may be removed from or mounted on the rack without unlocking the towels therefrom.

STEPHEN B. FETHEROLE.
